DESCRIPTION

FIG. 1 is a front perspective view of a set of keys for a handset showing our new design;

FIG. 2 is a front view thereof;

FIG. 3 is a right side view thereof;

FIG. 4 is a left side view thereof;

FIG. 5 is an enlarged front perspective view of the set of keys shown in FIG. 1;

FIG. 6 is an enlarged front view thereof;

FIG. 7 is an enlarged right side view thereof; and,

FIG. 8 is an enlarged left side view thereof.

The broken line showing of the remainder of the handset is directed to environment, is for illustrative purposes only, and forms no part of the claimed design.
